UNITED STATES PATENT OFFICE

ISRIAL H. SHAPACK, OF BROOKLYN, NEW YORK

DESIGN FOR A SHOE STRAP OR SIMILAR ARTICLE

Application filed February 20, 1931. Serial No. 38,746. Term of patent 3½ years.

To all whom it may concern:

Be it known that I, ISRIAL H. SHAPACK, a citizen of the United States of America, residing at Brooklyn, Kings County, city and State of New York, have invented a new, original, and ornamental Design for a Shoe Strap or Similar Article, of which the following is a specification, reference being had to the accompanying drawing, forming part hereof, in which Fig. 1 is a face view of a shoe strap or similar article, showing my new design, and Fig. 2 is an edge view thereof.

I claim:

The ornamental design for a shoe strap or similar article as shown.

Signed at New York city, New York, this 16th day of February, 1931.

ISRIAL H. SHAPACK.
